CLAMPING MECHANISM FOR LIFT TRUCKS
 Elmer G. Bjorklund and Louis A. Haddock, Jr., Battle
 Creek, Mich., assignors to Clark Equipment Company,
 a corporation of Michigan

Filed Dec. 21, 1961, Ser. No. 160,983
 4 Claims. (Cl. 294—88)

The present invention relates to a rotatable clamping device adapted to be used as an elevatable attachment on the lifting mast of an industrial lift truck, and to be utilized for transporting and stacking cylindrical objects of widely varying diameters, such as paper rolls or the like, in either vertical or horizontal positions.

More specifically, the invention relates to a clamping mechanism of the character mentioned comprising a pair of clamping arms mounted on slides and movable towards one another by hydraulic actuating means for clamping engagement with loads of various diameters, one of the clamping arms being rigidly secured to a first arm carrier slide member, and the other of the clamping arms being pivotally mounted on a second arm carrier slide member and guided by cam and cam follower means, whereby as the two arms are moved toward one another, one arm will also be pivoted inwardly toward the other to supplement and thereby accelerate the clamping action effected by rectilinear movement of the respective slide members.

One object of the present invention is to provide a clamping mechanism of the foregoing type having two opposed clamping arms, one of which is pivotally mounted on a corresponding arm carrier slide member by hinge pin means, and to provide in conjunction therewith cam and cam follower guide means for continuously controlling the pivotal position of said one arm.

Another object is to provide such a clamping mechanism embodying an arm carrier slide having an improved torque transfer member for transferring clamping forces from a pivotable clamping arm to a clamp base member, said transfer member comprising a torsion tube having a pair of mounting arms for hingedly supporting the pivotable clamping arm, and a pair of bearing plate members which carry bearing means thereon.

A further object of the invention is to provide a clamping mechanism as last aforementioned wherein each slide member carries two outwardly projecting parallel bearing plates, and each of said plates has a pair of spaced apart generally cylindrical bearings welded thereto and adapted for reciprocation in tubes which form elements of a clamp base structure.

The above and other objects will appear from the following detailed description of a preferred embodiment of the invention.

Now in order to acquaint those skilled in the art with the manner of utilizing and practicing our invention, we shall describe in conjunction with the accompanying drawings a preferred embodiment thereof.

In the drawings:

FIGURE 1 is a perspective view of a clamping mechanism constructed in accordance with the present invention and mounted on the lifting mast of an industrial lift truck, the clamping arms being shown in extended positions and a rotatable clamp base being shown intermediate its horizontal and vertical positions;

FIGURE 2 is an enlarged front elevational view showing the clamping mechanism rotated to its horizontal position, a front cover plate for the rotatable clamp base being removed to illustrate the interior parts thereof;

FIGURE 3 is an exploded perspective view illustrating certain elements of the clamping mechanism, particularly the rotatable clamp base and two arm carrier slides which are adapted to be mounted in said base for reciprocation

2

towards and away from one another, said view being substantially from the rear of the mechanism and showing the same rotated 180 degrees from the position of FIGURE 2; and

FIGURE 4 is a substantially enlarged perspective view showing the clamping arms in their approximate innermost positions with one arm pivoted inwardly toward the other.

FIGURES 1 and 4 show an industrial lift truck 20 having a lifting mast 22, the latter including an elevatable cross beam 24 (shown best in FIGURE 4) on which the clamping mechanism assembly is hung for movement upward and downward upon operation of the mast. The portion of the clamping mechanism assembly which is fixed with respect to the cross beam 24 includes a hanger plate 26 having attached thereto a pair of brackets 28 (one of which is shown) which hook over the upper edge of the beam 24 to hang the clamping mechanism thereon. If desired, the clamping assembly may also be bolted or otherwise further secured to the cross beam 24.

The fixed portion of the clamping mechanism assembly further includes a pair of double acting hydraulic cylinders 30 and 32 which serve to rotate a clamp base assembly 34 to permit loading, transporting, and stacking of paper rolls in either vertical or horizontal positions. The structure and operation of a rotating mechanism particularly suitable for use with the present invention is fully described in a co-pending application entitled "Carriage Rotating Mechanism for Lift Trucks and the Like," filed February 5, 1962, by William A. Norlander, Serial No. 170,879, and assigned to the assignee of the present invention.

FIGURES 1 and 3 show arm carrier slide members 36 and 38 which are mounted in the base 34 for reciprocation towards and away from one another, the slide 36 being adapted to carry a pivotable clamping arm 40, and the slide 38 being adapted to carry a rigid clamping arm 42.

The slide 36 (shown best in FIGURE 3) has a base comprising a torsion tube 44 which has welded thereto a pair of spaced parallel bearing plates 46 and 48 which are perpendicular to the tube 44 and extend outwardly therefrom toward the opposed slide 38. Welded to the plate 46 are a pair of generally cylindrical bearings 50 and 52 which are adapted to be enclosed by covers made of a suitable bearing material such as phenolic or nylon or the like, as shown at 53 and 54.

More specifically, the bearing 50 comprises a generally C-shaped member formed from a relatively thick flat disc or cylindrical member by cutting a flat-sided slot therein of a thickness approximately equal to the thickness of the bearing plate 46. The bearing 50 is assembled on the far inner end 59 of the plate 46 (the terms "inner" and "outer" being used herein with reference to the over-all clamping mechanism assembly) with the bottom of the slot seated against the forward edge of the latter, and the bearing is then welded in position, after which the bearing cover 53 is assembled thereover. The bearing 52 similarly comprises a relatively thick disc or cylindrical member which is provided with a flat-sided slot and is seated on the plate 46 near the outer end thereof and welded in position.

It will be noted that the inner bearing 50 is assembled on the plate 46 from the front thereof so that the slot in said member faces rearwardly, while the bearing member 52 is assembled in opposite fashion with the slot in said member facing forwardly. This is desirable since, under the forces developed during clamping operations, the bearing 50 will be urged rearwardly and the bearing 52 urged forwardly with respect to the bearing plate 46. The plate 48 is provided with bearings 62 and 63 which

are substantially identical to the above-described bearings 50 and 52.

A pair of parallel support arms 64 and 66 are welded to the torsion tube 44 axially outwardly of the bearing plates 46 and 48, said arms being disposed approximately at the respective ends of the tube. The support arms 64 and 66 extend generally forwardly from the torsion tube 44, and are provided at their forward ends with pivot pin holes 67 and 68, whereby the clamping arm 40 may be pivotally mounted thereon, as will be more fully described hereinafter.

A lug 70 is welded to the torsion tube 44 approximately midway between the bearing plates 46 and 48 and serves to anchor a hydraulically actuated piston (to be described later herein) to the slide 36 to permit reciprocation of the latter toward and away from the opposed slide member 38.

The slide member 38, provided to carry the rigid clamping arm 42, comprises a flat base plate 72 which has welded thereto a pair of spaced parallel bearing plates 74 and 76, and also a lug 77 positioned intermediate the bearing plates for permitting connection of the slide 38 to a corresponding hydraulically actuated piston. Bearings 78 and 79 are welded to the plate 74, and bearings 80 and 81 are welded to the plate 76, the bearings 78 and 79 being spaced from one another and being assembled on the plate 74 from the rear and forward sides thereof, respectively, and the bearings 80 and 81 being similarly spaced and assembled on the plate 76 from the rear and forward sides thereof, respectively.

Each of the four bearings for the slide 38 comprises a generally C-shaped member substantially as described hereinabove with respect to the bearing 50 on the opposing slide 36. A pair of bearing covers are indicated at 82 and 83, it being understood that one cover member made of a suitable bearing material such as nylon or phenolic is supplied for each of the four bearings on each slide member. Holes 84 are provided in the base plate 72 to permit the clamping arm 42 to be rigidly bolted to the slide 38.

FIGURE 2 shows the assembled position of the various elements of FIGURE 3 together with the clamping arms 40 and 42. The clamp base assembly 34 includes a first pair of tubes 86 and 88 in which the bearings 50 and 52 on the bearing plate 46, and the bearings 62 and 63 on the bearing plate 48, are slidably mounted, respectively. The tube 86 is provided with a longitudinal slot 90 to accommodate the plate 46, and the tube 88 is similarly provided with a longitudinal slot 92 to accommodate the plate 48. It will now be seen that the slide 36 is carried by the clamp base assembly 34 for reciprocation toward and away from the opposed slide 38, the four bearings on said slide 36 being slidably received within the tubes 86 and 88, respectively.

In a similar manner, the slide 38 is carried by the clamp base assembly 34 for reciprocation towards and away from the slide 36, the bearings 78 and 79 being received in a tubular member 94, and the bearings 80 and 81 being received in a tubular member 96. The tube 94 is provided with a longitudinal slot 97 to accommodate the bearing plate 74, and the tube 96 is similarly provided with a slot 98 to accommodate the plate 76.

The slides 36 and 38 are caused to reciprocate in the clamp base assembly 34 by means of a pair of double acting hydraulic cylinders 100 and 102. The cylinder 100 is anchored to the clamp base assembly by any suitable means, and a piston 104 associated therewith has a threaded outer end 105 (see FIGURE 3) which extends through a hole 105 in the mounting lug 70 which is welded to the torsion tube 44, a nut 107 serving to secure the piston 104 to said lug. Accordingly, slide 36 is reciprocated toward and away from opposing slide 38 by conducting fluid under pressure to an appropriate end of double acting cylinder 100. The cylinder 102 and a piston 108 associated therewith operate in similar fashion to reciprocate the slide 38, the piston 108 having a threaded end

portion 109 which extends through a hole 110 in the lug 77 and is anchored thereto by a nut 112. A front cover plate 114 is utilized to enclose the various elements of the clamp base assembly 34.

The clamping arm 40 (shown best in FIGURES 1 and 4) comprises a pair of contoured side plates 116 and 118, a front plate 120, and a back plate 122, all of said plates being welded together to form a unitary arm assembly. FIGURE 1 illustrates the manner in which the clamping arm 40 is pivotally mounted on the slide 36. It will be noted that the support arms 64 and 66 on the slide extend into respective clearances provided between the side plates 116 and 118 and the body portion of the clamping arm. A first hinge pin 125 extends through the hole 67 (see FIGURE 3) in the end of the support arm 64, and into both the side plate 116 and the body portion of the arm 40. A similar hinge pin, indicated generally at 126, extends through the hole 68 in the support arm 66, and into both the side plate 118 and the body portion of the arm.

The clamp arm 40 is pivotable outwardly with respect to the opposed clamp arm 42 until the rear edge of the back plate 122 bears against the torsion tube 44 in the areas where the support arms 64 and 66 are welded thereto, after which further outward pivotal movement of arm 40 is prevented. The arm 40 is shown approximately in its outermost pivotal position in FIGURE 1. It is important to note that no springs are needed to control the pivotal position of the arm 40 since cam and cam follower means, to be described below, are provided which continuously act to effect this function.

A roller 130 is rotatably carried on the end of the side plate 116 by a pin 132, and a similar roller 134 is rotatably carried on the end of the opposite side plate 118. A flat mounting plate 135 (shown best in FIGURE 3) comprises an element of the clamp base assembly, and a pair of cam blocks 136 and 138 are secured thereto by any suitable means. For example, screws as shown at 140, and shims as shown at 141, may be utilized for this purpose. The cam 136 is positioned to cooperate with the roller 130, and the cam 138 is similarly positioned to cooperate with the roller 134, whereby the arm 40 is prevented from pivoting inwardly until the slide 36 carries it inwardly an amount sufficient to permit the rollers 130 and 134 to roll off the ends of the cam blocks 136 and 138, respectively.

A second pair of sloping cams 144 and 145 are secured to the clamp base assembly for the purpose of engaging the rollers once they have passed over the ends of the cams 136 and 138, such engagement preventing further inward movement of the rollers and thus causing the arm 40 to pivot inwardly about hinges 125 and 126 toward the opposing arm 42 as the slide 36 continues its inward rectilinear movement. Referring to FIGURE 1, the tubular member 94 has a lug 146 attached thereto, and the cam 144 is mounted on said lug means by screws 147 in a position to engage the roller 130 when the latter moves inwardly beyond the cam plate 136. The cam 145 is similarly mounted on a lug 150 on the tubular member 96 in position to engage the roller 134 when the latter moves inwardly beyond the cam plate 138.

The clamping arm 42 (shown best in FIGURES 1 and 4) comprises a pair of contoured side plates 152 and 154, a base plate 156, a front plate 158 and a back plate 160, all of which are welded or otherwise suitably secured together to form a unitary arm assembly. The arm 42 is rigidly secured to the slide 38 by means of a plurality of bolts 161 which extend through the arm base plate 156 and through the slide base plate 72 rearwardly of which nuts 162 are applied, whereby the arm plate 156 is rigidly held in abutting relation against the plate 72.

Clamp pads 164 and 166 are hinged at the outer ends of the clamping arms by hinge pins 167 and 168, respectively, and such pads serve as load gripping members and engage and hold a paper roll or the like when the clamping arms are moved together sufficiently to permit a roll to be squeezed between the pads.

Each of the clamp pads may be provided with a pair of restraining rods or straps 170, with one end of each strap being hinged to a respective pad, and the other end slidably guided in tracks provided within the corresponding clamping arm. Such clamp pads are preferably biased to an outer position wherein the straps 170 are substantially retracted within the associated clamp arm, the pads being pivotable outwardly under load, but the latter pivotal movement being limited in accordance with the length of the strap members. A detailed description of clamp pads suitable for use with the present invention will be found in a copending application entitled "Clamp Pad for Roll Clamping Mechanism," filed December 27, 1961, by Kenneth H. Mindrum, Serial No. 162,339, and assigned to the assignee of the present invention.

It will be understood that when the clamping arms 40 and 42 are extended as shown in FIGURES 1 and 2, the arm 40 is held in its outer pivotal position by the cam blocks 136 and 138 which act upon the rollers 130 and 134 carried by said arm. The arm 40 will be continuously held in the outermost pivotal position until the slide 36 on which it is carried is moved inwardly an amount sufficient to permit the rollers 130 and 134 to roll off the ends of the cam blocks. If the slide 36 is then moved further inwardly, the rollers 130 and 134 will engage the sloping cams 144 and 145, causing the arm 40 to be pivoted inwardly as shown in FIGURE 4. When the slide 36 is again moved outwardly, the rollers will ride over the inner ends of the cams 136 and 138 so as to again bear against the sides thereof as shown in FIGURE 1, whereby the arm 40 will be returned to its outermost pivotal position. Accordingly, the pivotal position of the arm 40 is controlled at all times by the cam members, without need for any springs or other means to effect the desired positioning of said arm.

When the arms 40 and 42 are moved towards one another to clamp a paper roll or the like between the pivoted pad members 164 and 166, it will be seen that the clamping forces on the pad 164 are transmitted from the arm 40 to the hinge pins 125 and 126, which in turn load the support arms 64 and 66 and thereby apply torsional loads at the two ends of the torsion tube 44. Also, the force exerted by the piston 104 on the lug 70 is transmitted to the torsion tube. The foregoing loads are then transmitted from the tube 44 to the bearing plates 46 and 48, and finally to the four bearings 50, 52, 62 and 63 which are supported in the tubes 86 and 88 of the clamp base assembly 34.

It has been found that the torsion tube 44 provides an exceptionally strong and lightweight structure for transmitting clamping forces to the clamp base assembly 34, and that the bearings such as the bearing 50 are unusually simple to assemble to the bearing plates, and provide an effective expedient for slidably supporting the slide members 36 and 38.

It will be understood that various modifications and arrangements may be made in the embodiments selected for disclosing our invention without departing from the spirit and scope of the invention.

We claim:

1. In a clamping mechanism for lift trucks of the type having a pair of opposed clamping arms adapted to reciprocate inwardly towards and outwardly away from one another and having a main base portion with tubular members for guiding such movement, an arm carrier slide

member, comprising: a slide base, a pair of spaced parallel bearing plates secured to said slide base and extending therefrom toward said main base portion, and a pair of generally cylindrical bearings attached to each of said plates respectively, each of said bearings having a slot therein of a thickness approximately equal to the thickness of its respective bearing plate to facilitate seating of said bearings on said plates, one of each pair of bearings being rigidly mounted at the far inner end of a respective bearing plate, and the other of each pair of bearings being rigidly mounted adjacent the outer end of its respective plate, said bearings being adapted for reciprocation within said tubular members.

2. In a clamping mechanism for lift trucks of the type having a pair of opposed clamping arms adapted to reciprocate inwardly towards and outwardly away from one another and having a main base portion with tubular members for guiding such movement, an arm carrier slide member, comprising: a slide base, a pair of spaced parallel substantially flat bearing plates secured to said slide base and extending therefrom toward said main base portion, and a pair of bearings attached to each of said plates respectively, one of each pair of bearings being rigidly mounted at the far inner end of a respective bearing plate, and the other of each pair of bearings being rigidly mounted adjacent the outer end of its respective plate, each of said bearings being generally C-shaped and comprising a relatively thick disc having a flat-sided slot therein of a thickness approximately equal to the thickness of its respective bearing plate to facilitate seating of said bearings on said plates, said bearings being adapted for reciprocation within said tubular members.

3. In a clamping mechanism for lift trucks of the type having a pair of opposed clamping arms adapted to reciprocate inwardly towards and outwardly away from one another and having a main base portion with tubular members for guiding such movement, an arm carrier slide member, comprising: a slide base, a pair of spaced parallel substantially flat bearing plates secured to said slide base and extending therefrom toward said main base portion, and four bearings each of which is generally C-shaped and comprises a relatively thick disc having a flat-sided slot therein of a thickness approximately equal to the thickness of said bearing plates, one pair of said bearings being mounted on the far inner ends of respective bearing plates with their slots disposed rearwardly, and a second pair of said bearings being mounted adjacent respective outer ends of said plates with their slots disposed forwardly, said bearings being adapted for reciprocation within said tubular members.

4. The invention of claim 3 wherein each of said four bearings is seated on a respective plate member and welded thereto, and each is enclosed by a corresponding substantially tubular bearing cover member.
